(57) **CLAIM**

The ornamental design for a remote control housing, as shown and described.

DESCRIPTION

FIG. 1 is a perspective view of an ornamental design for a remote control housing, in an open configuration according to the invention.

FIG. 2 is a side view of an ornamental design for the remote control housing of FIG. 1 according to the invention.

FIG. 3 is a top view of an ornamental design for the remote control housing of FIG. 1 according to the invention.

FIG. 4 is a bottom view of an ornamental design for the remote control housing of FIG. 1 according to the invention.

FIG. 5 is an end view of an ornamental design for the remote control housing of FIG. 1 according to the invention.

FIG. 6 is an end view of an ornamental design for the remote control housing of FIG. 1 according to the invention; and,

FIG. 7 is a perspective view of an ornamental design for the remote control housing of FIG. 1, in a closed configuration, according to the invention.

The broken lines in the figures depict portions of the remote control housing that form no part of the claimed design.
